P. OESTERREICHER

PNEUMATIC PLAYER ACTION FOR PIANOS

Filed Sept. 15, 1921

Fig. 1

Fig. 2.

Inventor:
Peter Oesterreicher

By Tonee Bain Hinkle

Atty.

UNITED STATES PATENT OFFICE.

PETER OESTERREICHER, OF CHICAGO, ILLINOIS.

PNEUMATIC PLAYER ACTION FOR PIANOS.

Application filed September 15, 1921. Serial No. 500,891.

To all whom it may concern:

Be it known that I, PETER OESTERREICHER, a citizen of the United States, residing at Chicago, in the county of Cook and State of Illinois, have invented certain new and useful Improvements in Pneumatic Player Actions for Pianos, of which the following is a specification.

The invention relates to improvements in pneumatic player actions for pianos.

One of the objects of the invention is to provide an improved pneumatic piano player mechanism which may conveniently be placed in an ordinary piano and operated independently of the usual keyboard, and which will not interfere with the operation of the latter.

Another object is to provide an improved pneumatic action which may conveniently and quickly be removed from its support for repair or adjustment and as quickly replaced.

Another object is to provide a pneumatic action having a self-contained inseparable means for holding it in supported position to the wind-chest, or trunk, provided for a plurality of such actions, and by means of which the packing between the communicating openings is compressed and held in place.

Another object is to generally improve pneumatic actions for pianos.

Other, further and more specific objects of the invention will become readily apparent, to persons skilled in the art, from a consideration of the following description, when taken in conjunction with accompanying drawings, wherein:—

Fig. 1 is a plan view of two actions placed side by side and secured to a wind-chest showing parts of one action in section.

Fig. 2 is a section taken on line 2—2 of Fig. 1.

In both views the same reference characters are employed to indicate similar parts.

In the drawings 5 represents the fixed body part of one of the pneumatic actions, and 6 is the relatively movable part which imparts the necessary motion to the sticker rods of the piano, as usual in structures of this general character. The part 6 is hinged at 7 and is connected to the part 5 by the flexible bellows fold 8.

A recess 9 in the part 5 is covered by a very flexible diaphragm 10, which is also closed by the wall 8' to provide the chamber 10'

under the diaphragm, and a recess 11 contains a rotatably adjustable valve seat 12, which is vertically adjustable to limit the operative movement of the valve 13. There is an opening 14 between the recesses 9 and 11, within which the stem 15 of the valve is contained and thru which air passes to the wind-chest from the bellows 8. The valve normally closes the opening 14 and, when lifted by the diaphragm 10, it closes the opening 16 in the valve seat structure 12, which communicates, normally, with the recess 11 from the outside atmosphere.

17 is an elongated wind-chest, or trunk, containing a vacuum chamber 18 from which the air is normally exhausted to some extent by means of a pump which is operated in connection with the pneumatic actions of this character.

For each pneumatic action there is an orifice 19 extending thru the rear vertical wall of the wind-chest for communication with the interior of the action. An opening 20 extends from the orifice 19 to the chamber 9, and a small bleeder hole 21 extends from the wind-chest to the vent opening 22 which is in communication with the chamber 10' above the bellows. The opening 22 is connected by a pipe 24 and thereby to the usual tracker-board used in connection with devices of this character.

Two like air conduits 25 and 26 connect the chamber 11 with the chamber 23 within the bellows and normally vent said bellows chamber to the outside atmosphere when valve 13 is seated by effect of gravity. These conduits are amply large and offer relatively small resistance.

To the lower end of the hinge member 6 is secured a plate 27 upon the end of which a sticker rod (not shown) normally rests and by which the rod is lifted when the bellows is collapsed.

A bracket 28, secured to the part 29 by screws 30, is made of a relatively yielding material, such as spring sheet brass, or the like, being provided with a threaded boss 31 in which a screw 32 is adjustable. The screw may carry on its end a lug 33 for contact with the wind-chest 17. When the screw is tightened the piano action is brought into forcible contact with the packing 34 which is placed between the action and the wind-chest to prevent air leak. A pin 35 is the guide by which the action is held in relation to the wind-chest, so that it will always be

returned accurately to the place from which it was taken.

The operation of the device is substantially as follows:

- 5 When the tube 22 is closed by the moving strip on the tracker board, the subatmospheric pressures above and below the diaphragm 10 is substantially balanced by communication thru the bleeder tube 21. There-
- 10 fore the attenuation of air in the chamber 18 of the wind-chest will not raise the member 6. If now, the tube 22 be opened, as when the moving strip on the tracker board presents a slot immediately over the end of
- 15 the tube 24, pressure in chamber 10' will equal that of the atmosphere, and the diaphragm 10 will be raised as a result of atmospheric pressure and air attenuation in chamber 9, closing port 16 and causing air
- 20 to pass from the bellows chamber 23, thru air conduits 25 and 26 to chamber 11, thru port 14, now open, into chamber 9, thru opening 20 into chamber 18 of the wind chest 17. This causes the collapse of the
- 25 bellows fold 8, raising the member 6 and plate 27 and thereby the sticker rod. When

the tube 24 is again closed by further movement of the strip, equilibrium is established. valve 13 will fall, opening port 16 and closing port 14, causing the bellows fold to be again expanded.

Having described my invention what I claim as new and desire to secure by Letters Patent, is:—

1. A pneumatic action having an aperture 35 and a wind chest having a registering aperture, in combination with a dowel pin to hold the apertures in register, and a resilient clamping means to hold the action and chest together. 40

2. A pneumatic action having an aperture thru a vertical wall and a wind chest having a registering aperture thru a vertical wall in combination with a horizontally disposed dowel pin to hold the apertures in 45 register; a resilient bracket, and a screw co-operating therewith and adjustable in the bracket to clamp the action and chest together.

In testimony whereof I hereunto sub- 50 scribed my name.

PETER OESTERREICHER.
